UNITED STATES PATENT OFFICE.

GARRY J. DORMANDY, OF TROY, NEW YORK, ASSIGNOR TO LION COLLAR & SHIRTS, INC., OF TROY, NEW YORK, A CORPORATION OF NEW YORK.

SEWING MACHINE.

Application filed June 27, 1925. Serial No. 39,888.

This invention relates to a sewing machine by which a plurality of rows of stitches can be sewed simultaneously. It relates more particularly to a device of this sort in which one of the needles can be started and stopped by the work at predetermined points with respect to the work. This invention is especially adapted to the sewing of two rows of stitches near the edges of work, such as, 5 cuffs and collars, for example, although it is not restricted to this particular use. In sewing parallel stitches near the edges of work, it is well known that the inside row of 10 stitches is shorter on account of corners or curves than the outside row. For this reason it is desirable that when corners are 15 turned, the needle which sews the inside or shorter row of stitches should cease operating, while the outside needle is sewing the 20 row of stitches near the corner.

By the present invention, means are provided by which one needle can begin sewing a row of stitches at the desired point, and another needle can be automatically 25 thrown into operation to begin sewing at a predetermined distance from the edge of the work or cloth. The latter needle is also caused to stop automatically at a predetermined point before the rear edge of the 30 work or cloth is reached. The operations of starting and stopping the needle are controlled by the work itself.

The invention will be understood from the description in connection with the accompanying drawings, in which Fig. 1 is 35 a side view of a sewing machine showing the invention; Fig. 2 is a front view of the same; Fig. 3 is a side elevation of an attachment made in accordance with the invention; Fig. 4 is a similar view from the other side; Fig. 5 is a section along the line *a—a* of Fig. 4; Fig. 6 is a side view of a modification; Fig. 7 is a plan view of the same; Fig. 8 shows an article sewed in accordance with this invention and Fig. 9 is 45 a sectional view showing one of the details of the machine.

In the drawings, reference character 1, indicates a sewing machine of the usual construction which is provided with a split needle bar consisting of two halves 2 and 3, each carrying a needle at its lower end. These two halves 2 and 3 of the needle bar may be caused to sew by the operating mechanism of the machine, in the usual way, so

that one or both may be caused to sew in accordance with the desired conditions. A collar 4 surrounds the bars 2 and 3 and a pin 5 passes through holes in the collar 4 and the bars 2 and 3, as is more clearly indicated in Fig. 9. The pin 5 carries a head 6 having a hole therethrough, so that this head is adapted to slide up and down on the rod 7. A stationary stop 8 is provided, with the upper end of which the head 6 60 may be caused to come into contact. The rod 7 is mounted upon a shaft 9 that is revoluble in bearings 10, a set screw 11 holding the rod 7 upon the shaft 9. A crank arm 12 on the shaft 9 is connected by means of the connection 13 to one arm of the bell crank 14, which is pivoted at 15 to the machine, the other arm of this bell crank being connected to a spring-pressed rod 16 having a compression spring 75 17 surrounding the lower end thereof and tending to force the rod 16 upwardly by bearing against an adjustable collar on this rod. The rod 16 carries an adjustable collar 18 upon which a bifurcated arm 19 preses. 80 This arm 19 is connected to the armature 20 of an electro-magnet 21, which armature is pivoted at 22. An extension 23 of the arm 19 carries an adjustable stop 24 and a tension spring 25 connects the lower end of 85 the extension 23 to a fixed pin.

The two halves 2 and 3 of the needle bar carry the needles 26 and 27, respectively. These needles move up and down through holes 28 and 29 in the presser foot 30 (Fig. 5), this presser foot being capable of being lifted temporarily by the lever 31 of the usual and well-known sort for the insertion of work. L-shaped levers 33 and 34 are pivoted on the presser foot 30 at 35 and 95 36. These levers are provided at their upper ends with electrical contacts 37 and 38, that are insulated from the levers. Springs 39 and 40 on the presser foot 30 urge the levers 33 and 34 in a clockwise direction, as seen 100 in Fig. 3. The lower arms of the levers 33 and 34 are provided with slots 41 and 42, in which members 43 and 44 are adjustably mounted by means of the screws 45 and 46. The forward ends of the members 43 and 44 105 are rounded on the underside to facilitate entry of the work. Both the electrical contacts 37 and 38 are connected to one side of a source 45, of electric current. The current from this source also passes through the 110

magnet 21 and to the other terminal 46, which is electrically connected to the other contacts 47 and 48. A guide bar for the work is shown at 49 (Figs. 1 and 6) and the rest plate or table for the work is shown at 50.

In the modification shown in Figs. 6 and 7, an insert 60 is flush with the rest plate for the work. A metal plate 61 is attached to 10 but insulated from the insert 60. This plate 61 is provided with lugs or projections 62, 63, the upper faces of which are flush with the upper face of the insert 60. The other elements in this modification are similar to 15 those already described and are designated by the same reference characters with primes. It is, therefore, thought unnecessary to repeat the description in detail.

For ready understanding of the operation 20 of the device, it should be kept in mind that only one needle, namely, the one operated by the bar 2, is operative initially, and it is only after this needle has sewed a predetermined distance from the edge of the cloth that the 25 other needle begins to sew. Also as soon as the needle 26, operated by the bar 2, is within a certain distance of the rear edge of the cloth, the other needle ceases to operate. The needle 27 is caused to begin and to cease 30 operating in accordance with the progress of the cloth or work. The principle that is utilized to cause this result to be accomplished is that as long as either one of two electrical contacts are closed, the needle 27 35 is kept from operating. When the sewing at the edge of the cloth is first begun, one of the contacts is closed and the other open so the needle 27 does not operate and after the cloth has progressed a certain distance, 40 both contacts are open, thereby permitting needle 27 to operate, and when the needle 26 has reached a predetermined position near the other edge of the cloth, the other contact is closed and the needle 27 ceases to operate. 45

The operation is as follows: As long as either contact between 37 and 47, or the contact between 38 and 48 is closed (Fig. 3), a complete circuit will be closed from the battery 45, through the closed contact or contacts to the terminal 46, and through the magnet 21 back to the battery. This will energize the electro-magnet 21, drawing down its armature 20 (Fig. 2), together with 50 the arm 19 which pulls the rod 16 downwardly, thereby turning the bell crank 14 (Fig. 1) and causing the connection 13 to turn the shaft 9, thereby pulling the rod 7 and pin 5 to the right, thus permitting the 55 end of the pin to be pulled out of the hole in the bar 2 (Fig. 9) so that the bar 2 will slide with its flat face in contact with the flat face of the bar 3 without moving the bar 3. Also the head 6 of the pin 5 will rest upon 60 the top end of the stop 8, thus preventing the 65

bar 3 from operating, due to fact that the pin 5 still projects into the hole in this bar. As soon as the magnet 21 is de-energized, the springs 25 and 17 (Fig. 2) cause the bell crank 14 to be turned clockwise (Fig. 1) by 70 means of rod 16, thus turning the rod 7 to the left and causing the pin 5 to project into the hole in the bar 2, as soon as this hole reaches the pin 5, and its head 6 to move out of the way of the stop 8, so that both bars 2 75 and 3 carrying the needles 26 and 27 will be operated together. The magnet 21 is de-energized by the work itself as will be understood from an inspection of Fig. 3. As the work advances toward the left in this figure, its forward edge raises the member 43, thus turning the lever 33 on the pivot 35 and opening the contacts 37, 47. As soon as the forward edge of the cloth reaches the needle 26, this needle begins to sew its row of 80 stitches, while the needle 27 is idle. When the forward edge of the work reaches the member 44, this member is likewise raised by the cloth, thus turning the lever 34 on its pivot 36 and opening the contacts 38, 48 and 85 breaking the circuit through the magnet 21. As soon as this circuit is broken, the needle 27 is put into operation as above described, and both needles continue to sew until the magnet is again energized. This magnet 90 will become energized as soon as the rear edge of the cloth passes out from under the member 43, thus permitting the spring 39 to turn the lever 33 and close the contacts 37, 47. As soon as this contact is closed, the 95 magnet 21 is energized and the needle 27 is stopped from operating, as above described. It will be understood that the distance that the needle 26 sews before the needle 27 begins to sew will be determined by the distance from the hole 28 in which the needle 26 works to the bottom edge of the member 44, and the distance from the rear edge of the cloth at which the needle 27 stops sewing will depend upon the distance from the hole 100 28 through which the needle 26 works to the underside of the member 43. The members 44 and 43 are made adjustable so that the points at which the needle 27 begins and ceases operating can be varied. 105

In the modification shown in Figs. 6 and 7, the operation is similar to that already described. This modification is especially useful in cases where the cloth is so thin that the levers 33 and 34 of Fig. 3 would not be 110 turned sufficiently to open the contacts with certainty. In this modification the cloth itself breaks the circuit by moving between the lower ends or toes of the members 43', 44' and the projections 62 and 63 on the 115 plate 61. As long as the contacts between 43' and 62, or the contacts between 44' and 63 are closed, the magnet 21 will be energized and the needle 27 will be prevented from operating. As soon as the forward edge of 120 125 130

the cloth has proceeded sufficiently far to open both these contacts, the magnet 21 will be de-energized and the needle 27 will begin to sew, and as soon as the rear edge of the cloth has passed from between the contacts 43' and 62, the magnet 21 will be energized and the needle 27 will cease to sew.

The sort of results that can be obtained by this invention can be understood from Fig. 8 in which the end of a collar sewed by this device is shown. Assuming that the two rows of stitches were sewed in the direction of the arrow S, one can see that the left hand row was sewed by the needle 26 and the right hand row by the needle 27. As soon as the edge 70 passed out from under the member 43, the needle 27 stopped automatically at the point 71 and the needle 26 continued to the point 72 where it was stopped by the operator in the regular way. When the corner was turned and the needle 26 continued to sew in the direction of the arrow S', the needle 27 did not begin again until the point 71 was reached by it, the needle 27 being caused to begin again by the edge 73 passing under the member 44. The two rows of parallel stitches illustrated in the lower portion of Fig. 8 were sewed in the direction of the arrows S'', in a manner similar to that already described.

I claim:

1. In a device for sewing a plurality of rows of stitches, a needle for each row of stitches, and means operated by the work to cause one of said needles to begin sewing when another needle has sewed a distance approximately equal to the distance between two needles, said first named needle being inactive while the work is absent.

2. In a device for sewing a plurality of

rows of stitches, a needle for each row of stitches, and means operated by the work to cause one of said needles to begin sewing after another one has sewed a predetermined distance and to cause it to cease sewing at a predetermined distance from the edge of the work, said needle being inactive while the work is absent.

3. In a device for sewing rows of stitches, needles operated from a common source, and means operated by the work to start one of said needles after the work has advanced and then been sewed a predetermined distance by the other needle, said first named needle being inactive while the work is absent.

4. In a device for sewing rows of stitches, needles operated from a common source, and means operated by the work to start one of said needles after the work has advanced a predetermined distance from one edge of the work and to stop it before the other edge of the work has been reached by said needle, said needle being inactive while the work is absent.

5. In a device for sewing rows of stitches, needles operated from a common source, and means including an electro-magnet operated by the advancing edge of the work to start one of said needles to sewing and by the receding edge to stop it.

6. In a device for sewing rows of stitches, needles operated from a common source, one of said needles being continuously operated and another intermittently operated, and means including an electro-magnet operated by the advancing edge of the work to start said intermittently operated needle to sewing and by the receding edge to stop it.

GARRY J. DORMANDY.
